FIG. 1

FIG. 2

FIG. 5

FIG. 3

FIG. 4

FIG. 6

FIGURE 1 is a perspective view of a cutting tool, showing my new design.

FIGURE 2 is a top plan view.

FIGURE 3 is a side elevation.

FIGURE 4 is a bottom plan view.

FIGURE 5 is an end elevation taken from the left-hand side of FIGURE 3.

FIGURE 6 is a horizontal section taken on the lines 6—6 of FIGURE 1.

The characteristic feature of my design for cutting tool

is the step-like configuration of the merging areas of the vertical sides of the central portion thereof and the non-diverging non-vertical sides of the end portions thereof as best shown in FIGURES 1, 5 and 6.

I claim:

The ornamental design for a cutting tool, as shown and described.
